ROTARY MACHINE

Lewis Emanuel Zerbe, Moneta, Calif., assignor to
The National Superior Company, Toledo, Ohio,
a corporation of Delaware

Application February 21, 1934, Serial No. 712,385

8 Claims. (Cl. 255—23)

This invention relates to rotary machines, and more particularly to rotary drilling machines of the type generally employed in the drilling of wells for the recovery of oil, gas and water.

This invention is directed to an improvement in a rotary machine, as illustrated, for example, in Patent No. 1,876,126 to L. E. Zerbe et al., issued Sept. 6, 1932, for Rotary drilling machine.

An object of this invention is to provide a rotary drilling machine, including a circulatory oil system for the circulation of lubricant to gears and bearing, so that the gears and bearing are continuously supplied with lubricant while under operation.

Another object of this invention is to provide a unitary drive mechanism for driving the rotary table of a rotary machine of such construction as to enable the top of the rotary table to be positioned near the floor of the derrick for the convenience of the workers and operator.

Another object of this invention is to provide a rotary machine, including a right angle unitary drive mechanism for driving the rotary table drive gear.

Another object of this invention is to provide a rotary machine of the type in which the rotary table is positioned and constructed so as to move vertically with reference to the base in which the drive means for the rotary table is of unitary right angle construction, so that it may be assembled at or re-removed from the base in driving position, as desired or required, for repair or replacement.

Other objects and advantages of this invention it is believed will be apparent from the following detail description of a preferred embodiment thereof, as illustrated in the accompanying drawings.

In the drawings:

Figure 1 is an elevational view, mainly in vertical mid-section, of a rotary machine embodying my invention;

Figure 2 is a top plan view, partly in horizontal section, thereof;

Figure 3 is a fragmentary view, partly in vertical section, showing the unitary drive mechanism shifted radially from the rotary machine preparatory to lifting the unit from the machine;

Figure 4 is a fragmentary view, principally in vertical section, taken substantially on the line 4—4 of Figure 2, illustrating a portion of the oil circulatory system embodied in my invention;

Figure 5 is a fragmentary view, principally in vertical section and taken substantially on the line 5—5 of Figure 2 and positioned adjacent Fig-

ure 4 to illustrate the manner and system of oil circulation embodied in my invention;

Figure 6 is a fragmentary sectional view on an enlarged scale, taken substantially on the line 6—6—6—6 of Figure 5, illustrating the pinion shaft housing;

Figure 7 is an enlarged view, taken substantially on the line 7—7 of Figure 5, illustrating the oil circulating pump with the cover removed;

Figure 8 is a fragmentary sectional view, taken substantially on the line 8—8 of Figure 1;

Figure 9 is a fragmentary sectional view of a modified form of construction of unitary shaft drive assembly.

In the preferred embodiment of my invention, as illustrated in the accompanying drawings, 1 indicates the base of the rotary machine which is supported on I-beams 2. The base 1 has a vertically extending opening, in which is positioned the horizontal drive gear 3. The drive gear 3 is supported with relation to the base 1 by down-thrust and up-thrust bearings 4 and 5, respectively.

Mounted within the horizontal drive gear 3, so as to be vertically movable with relation to the drive gear 3 and so that the drive gear will drive the same, is the rotary table 6. The rotary table 6 has a depending sleeve 7 which is concentric within the gear 3 and is connected thereto by the interfitting vertical ribs and grooves 8 and 9 formed between the gear and sleeve, respectively.

The rotary table 6 is supported to move or be moved vertically with reference to the base 1 by means of a horizontal spider 10 to which three depending vertical piston rods 11 are secured. In order to support the table 6 relative to the spider 10, supporting and up-thrust bearings 12 and 13 are provided, permitting rotation of the table within the spider 10. The spider 10 is formed with an upstanding annular rim 14 which closely fits an annular downwardly extending outer rim 15 of the table 6 to provide a labyrinth path to exclude rotary mud or other foreign matter from the bearings 12 and 13. The inner edge of the spider 10 is formed to provide an inner upstanding wall 16 to form with the rim 14 a lubricant chamber, in which the bearing 12 is positioned.

The upthrust bearing 13 is held in position by means of a supporting ring 17, which is threaded to the sleeve 7 and held from rotation by a dowel 18. The ring 17 is formed with an outer annular wall 19 to retain lubricant for the bearing 13.

The piston rods 11 extend through cylinder caps 20. The cylinder caps 20 are secured to the cylinders 21. The cylinder caps 20 are clamped 55

to the base 1 by means of bridge pieces 22. The cylinder caps 28 contain liners 23 through which the rods 11 extend. The cylinders 21 are closed at their lower ends by means of caps 24. The 5 caps 24 are connected by the ring 25 having a fluid passage 26. The passage 26 is in communication with the interior of the cylinders 21 through ports 27 and is connected at 28 with a source of hydraulic pressure. The piston rods 11 are secured to pistons 29 within the cylinders 10 21.

Fluid under pressure may also be admitted or released to or from the opposite side of the pistons 29 through ports 30 formed in the caps 28 in communication with the recess 31 formed in the said caps 28 and connected through horizontal passages 32 with the annular passage 33 formed in the base 1. The passage 33 receives or discharges fluid under pressure through a port 20 34 to any suitable source of fluid under pressure.

The table 6 may be either raised or lowered under fluid pressure relative to the base 1. When the table 6 is rested on the upper ends of the cylinder caps 28, as illustrated in Figure 1, it is 25 in position to and may be used as an ordinary rotary drilling machine.

The rotary table 6 is rotated with reference to the base 1 by means acting in conjunction with the gear ring 3, which means includes a right angle unitary drive mechanism, preferably constructed as will hereinafter be described so as to enable the drive connection thereof to the source of power, whether rotary drawworks or other drive, to be raised up to the upper level 35 of the rotary table 6, or so that the entire rotary machine may be positioned down in the drilling rig with the top of the table 6 a minimum distance above the derrick floor level when used as a standard rotary machine.

The gear ring 3 is supported by the supporting bearing 4 positioned within a lubricant chamber 35 formed by the inner annular wall 36 of the base 1 to retain lubricant around the bearings when the rotary machine is stopped. The 40 up-thrust bearings 5 are positioned between the ring 3 and an up-thrust bearing ring 37, which is removably secured to the upper end of the base 1. Shims 38 are interposed between the thrust ring 37 and base 1 to provide for the adjustment of the bearing clearance of the bearings 5 and 4. The thrust ring 37 is formed with spaced annular rims 39, which interfit complementary annular rims 40 of a cover plate 41 to provide a labyrinth path to restrict the entrance 55 of rotary mud or other foreign matter into the bearings 5 and 4. The plate 41 is removably bolted to the gear ring 3.

The right angle unitary drive mechanism is preferably of the following construction:

The base 1 is formed with an extension 42 upon which the right angle unitary drive means is supported. This mechanism, as illustrated in the form of structure shown in Figures 1 to 8 inclusive, includes a gear 43 in mesh with the gear 3. The gear 43 is secured to the vertical shaft 44. The shaft 44 carries at its upper end the beveled gear 45 which meshes with the beveled pinion 46 secured to the horizontal pinion shaft 47. Secured to the pinion shaft 47 is the 60 sprocket wheel 48 which is driven from any suitable source of power such as, for example, a drawworks (not shown) or any other desired form of rotary drilling machine drive mechanism.

The vertical drive shaft 44 is rotatably sup-

ported by bearings 48 and 49. The lower bearing 48 is supported within a cap member 50 which registers in an opening 51 formed in the extension 42 and is secured in position by means of cap screws 52. The upper bearing 49 is mounted within a sleeve 53 that registers in an opening 54 of the housing 55. The housing 55 houses the unitary drive mechanism. The sleeve 53 is secured to the housing 55 by screws 56. In order to adjust the bearing clearance of the bearings 48 and 49, shims 57 are inserted between the meeting faces of the sleeve 53 and housing 55. 10

Bearings 58 and 59 are provided for the bevel pinion shaft 47. The bearings 58 and 59 are mounted within the sleeve 60 and sleeve cap 61 respectively within the housing 55. In order to adjust the axial position of the bevel pinion 47 and to adjust the axial position of the bearings 58 and 59 relative to the shaft 47, shims 62 and 15 63 are interposed between the flanges of the sleeve 60 and housing 55 and sleeve cap 61 and sleeve 60, respectively.

The sleeve 60, sleeve cap 61, shaft 47, bearings 58 and 59, and pinion 47, are insertable as a unit through the opening formed in the housing 55. 20 This opening is normally closed by the unit construction.

Means are provided for locking the pinion shaft 47 from rotation, and this means includes a lock ring 62 mounted on the shaft 47. Pawls 63 (one 30 of which is illustrated only in Figure 6) are provided within the housing 55 to engage the lock ring 62. The locking means provided by the lock ring 62 and pawls 63 are, or may be, of the general construction as illustrated in the copending application of David S. Faulkner, et al., Serial No. 504,758, for Rotary machine, filed December 26, 1930. 35

In order to remove the unitary right angled drive mechanism, including the housing 55 with the shafts 44 and 47 in position and carrying their assembled parts, it is necessary first to remove the plate 64 to gain access to the oil pump 65 and to remove the pump through the opening 66. The cap member 50 is then removed, together with the oil circulation tube 67. The housing 55, together with the shafts 44 and 47 and assembled parts, are then shifted as a unit radially from the gear 3 so that the unit can be raised vertically from the base extension 42. The opening 51 formed in the base extension 42 is proportioned so as to permit of sufficient shifting of the gear 43 to clear the opening in the top of the base extension 42 when the unit is lifted vertically from the rotary machine. 55

In order to provide for continuous circulation of oil to the bearing and gears within the base 1 and housing 55, I prefer to mount the oil pump 65 in a lubricant reservoir 68 formed in the base 1. The lubricant pump 65 may be of any suitable type and is here illustrated as a gear pump having meshing gears 69 and 70. 60

The gear 69 is mounted on a shaft 71 which extends through the pump housing and is driven by a gear 72 mounted on the upper end of the shaft 71 and in mesh with the gear 43. The pump 65 is normally below the lubricant level in the reservoir 68 and has an inlet or suction port 73 within the oil reservoir by means of a nipple 74 attached to the pump housing. The pump outlet 75 communicates with a passage 76 in the base extension 42 through a passage 77 formed in the pump housing. 70

The tube 67 secured to the cap member 50 in 75

communication with the passage 76 conducts the oil discharge from the pump 65 to a point above the gear 45. The tube 67 extends axially of the shaft 44 and above the gear 45 is provided with a plurality of radial openings 78 through which openings the lubricant is discharged to fill the portion of the housing 55 above the gear 45 with lubricant to approximately the oil level indicated by the dotted lines 79. The meshing beveled gears 45 and 46 are thus continually operating in a bath of lubricant. The lubricant likewise flows through the end of the sleeve 60 to continuously supply lubricant to the bearings 58 and 59.

15 Lubricant likewise flows from its position above the gear 45 under the gear 45 downward to fill the lubricant retainer 80 mounted on the shaft 44 to provide an oil bath for the bearing 49. The lubricant retainer 80 insures lubricant for the bearing 49 when the machine is stopped and then restarted. Lubricant overflowing from the chamber above the gear 45 and returning from any of these sources to within the housing 55 below the retainer 80 passes through the lubricant port 81 20 into the reservoir 68.

25 Lubricant from above the gear 45 also flows through the conduit 82 into the passage 83 formed in the ring 37, and flows through the passage 83 to the upthrust bearing 5. Lubricant passes from 30 the upthrust bearing 5 down to the supporting bearing 4 and to the gear 3. Lubricant as carried by the gear 3, lubricates the gear 43 and likewise the gear 72 on the pump shaft. Lubricant leaving the lower supporting bearing 4 35 passes through the port 84 and returns to the reservoir 68 through the port 81.

30 A vent 85 communicating through a passage 86 with the chamber above the reservoir 68 prevents the accumulation of air under pressure 40 within the housing 55 which would otherwise occur if no vent were provided to take care of the air displaced by the supply of oil circulated by the pump 65.

45 The oil reservoir 68 in the base is supplied with lubricant through an opening having the plug 87, and lubricant is drained through the opening having the plug 88.

50 The modification of my invention shown by Figure 9 provides for a self-contained bearing for the vertical drive shaft so that axial adjustment for the bevel pinion can be made and maintained with the housing removed from the machine.

55 In this modification of my invention, similar parts are indicated with the same numerals with the addition of an exponent "a" thereto. In this modification of my invention, the housing 55a encloses and supports the bevel gears 45a and 46a. The drive shaft 44a is rotatably supported by the bearings 48a and 49a. The upper bearing 49a is mounted within the sleeve 53a. The bearing 49a is a combined radial and thrust type bearing which is capable of taking axial thrust loads in either direction. The bearing 49a is held against axial movement by a ring 90 threaded in the sleeve 53a. Shims 51a between the faces of the sleeve 53a and housing 55a provide for axial adjustment of the sleeve 53a and the gear 45a. An oil container 80a is carried by the shaft 44a and forms a reservoir for retaining lubricant around the upper bearing 49a.

70 The lower bearing 48a of the radial type is retained in the cap 50a secured to the lower face of the extension 42a of the base 1a by means of bolts 52a. The cap 50a registers with the open-

ing in the base extension 42a to insure accurate bearing alignment for the bearings 48a and 49a.

75 The sleeve 53a is formed with a downwardly depending portion 91 to conduct lubricant overflowing the retainer 80a downward onto the inwardly inclined web 92 of the gear 43a. The lubricant thus collected drains through an opening 93 in the web into an enclosure 94 formed around the lower bearing 48a to retain a supply of lubricant for the bearing 48a when the operation of the machine is discontinued.

10 Having fully described my invention and modifications that the same may take, it is to be understood that said description is illustrative only and my invention is not limited to the details herein set forth, but is of the full scope of the appended claims.

15 I claim:

1. In a rotary machine, having a base and a gear ring rotatably supported by the base, the combination of a vertically extending pinion shaft having an axially extending bore formed therein, a drive pinion non-rotatably secured to said pinion shaft to mesh with said gear ring, bearing means to rotatably support said shaft on said base, a driven gear non-rotatably secured to the upper end of said shaft, a drive gear meshing with the driven gear, conduit means positioned within the shaft bore being supported adjacent the lower end of said shaft on said base, means to force 20 lubricant upwardly through said conduit means to lubricate said drive and driven gears, and means to enclose said last named gears.

2. In a rotary machine having a base and a gear ring rotatably supported by the base, the combination of a vertically extending pinion shaft having an axially extending bore formed therein, a drive pinion non-rotatably secured to said pinion shaft to mesh with said gear ring, a cap member removably secured to the base, 25 bearing means within said cap member to rotatably support the lower end of said shaft, a cover member removably secured to the base, bearing means within said cover member to rotatably support the upper end of said shaft, a bevel gear non-rotatably secured to the upper end of said shaft within said cover member, a bevel pinion adapted to drive said bevel gear, conduit means positioned within the shaft bore and secured to said cap member, and means to force lubricant upwardly 30 through said conduit means to lubricate said bevel pinion and gear.

3. In a rotary machine having a base and a gear ring rotatably supported by the base, the combination of a vertically extending pinion shaft 35 having an axially extending bore formed therein, a drive pinion non-rotatably secured to said pinion shaft to mesh with said gear ring, a cap member removably secured to the base, bearing means within said cap member to rotatably support the lower end of said shaft, a cover member removably secured to the base, bearing means within said cover member to rotatably support the upper end of said shaft, a bevel gear non-rotatably secured to the upper end of said shaft within said cover member, a bevel pinion adapted to drive said bevel gear, conduit means positioned within the shaft bore and secured to said cap member, means to force lubricant upwardly through said conduit means to lubricate said bevel pinion and gear, 40 and means carried by said shaft below the bevel gear to form a lubricant retainer around the latter bearing means and retain a portion of the lubricant draining from the gear.

4. In a rotary machine having a base and a 45

- 5 gear ring rotatably supported by the base, the combination of a vertically extending pinion shaft a drive pinion non-rotatably secured to said pinion shaft to mesh with said gear ring, a cap member removably secured to the base, radial bearing means within said cap member to rotatably support the lower end of said shaft, a cover member removably secured to the base, a bearing housing sleeve detachably secured to said cover member, bearing means within said sleeve to rotatably support said shaft against radial and up and down thrust loads, a bevel gear non-rotatably secured to the shaft above said drive pinion and within said cover member, and a bevel pinion adapted to drive said bevel gear.
- 10 5. In a rotary machine having a base and a gear ring rotatably supported by the base, the combination of a vertically extending pinion shaft, a drive pinion non-rotatably secured to said pinion shaft to mesh with said gear ring, a cap member removably secured to the base, bearing means within said cap member to rotatably support the lower end of said shaft, a cover member removably secured to the base, a bearing housing sleeve removably secured to said cover member, bearing means within said sleeve to rotatably support said shaft, a bevel gear non-rotatably secured to the shaft above said drive pinion and within said cover member, and a bevel pinion adapted to drive said bevel gear.
- 15 6. In a rotary machine, the combination of a base having a vertically extending opening therein and defining an annular rim at the upper end thereof, a gear ring rotatably supported within said base, an outwardly extending gear case secured to said base, a pinion shaft housing releasably secured to the upper face of said gear case to define an enclosure, an opening in the bottom wall of said case, a cap member detachably secured to the case and closing said opening, a vertically extending pinion shaft, a drive pinion non-rotatably secured to said shaft, said pinion in driving position extending in part through an opening in the wall of said base below the rim thereof to mesh with said gear ring, bearing
- 20 means supported by said cap member to rotatably support the lower end of said shaft, bearing means supported by said housing to rotatably support the upper end of said shaft, a bevel gear within said housing being non-rotatively secured to said shaft above said drive pinion, a bevel pinion rotatably supported within said housing and adapted to drive said bevel gear, said drive pinion and pinion shaft being removable through the opening in the top of said gear case upon removing the cap member and shifting the housing laterally relative to said gear ring to a point where the pinion will clear the rim of said base.
- 25 7. In a rotary machine, having a base and a gear ring rotatably supported by the base, the combination of a vertically extending pinion shaft having an axially extending bore formed therein, a drive pinion non-rotatably secured to said pinion shaft to mesh with said gear ring, bearing means to rotatably support said shaft on said base, a driven gear non-rotatably secured to the upper end of said shaft, a drive gear meshing with the driven gear, conduit means positioned within the shaft bore, means to support said conduit means, means to force lubricant upwardly through said conduit means to lubricate said drive and driven gears, and means to enclose said last named gears.
- 30 8. In a rotary machine having a base and a gear ring rotatably supported by the base, the combination of a vertically extending pinion shaft, a drive pinion non-rotatably secured to the pinion shaft to mesh with the gear ring, a cover member detachably secured to the base, a bearing housing sleeve detachably secured to the cover member, a cap member detachably secured to the base, bearing means for the shaft within the cap member, bearing means for the shaft within the bearing housing sleeve, one of said bearing means being adapted to support the shaft against up-and-down thrust loads, a driven gear non-rotatably secured to the shaft above said drive pinion and within the cover member, and means to drive the driven gear.

LEWIS E. ZERBE. 45
